UNITED STATES PATENT OFFICE.

FRANK. E. SAGENDORPH, OF CHICAGO, ILLINOIS, ASSIGNOR OF ONE-HALF
TO E. STARR LLOYD, OF SAME PLACE.

SHEET-METAL ROOF.

SPECIFICATION forming part of Letters Patent No. 357,041, dated February 1, 1887.

Application filed November 26, 1886. Serial No. 219,873. (No model.)

To all whom it may concern:

Be it known that I, FRANK. E. SAGENDORPH, of Chicago, in the county of Cook and State of Illinois, have invented certain new and useful 5 Improvements in Sheet-Metal Roofs, of which the following is a description, reference being had to the accompanying drawings, forming a part of this specification, in which—

Figure 1 is a plan view of a portion of a 10 sheet-metal roof, partly completed and partly in course of construction, and showing my improvement applied thereto. Fig. 2 is a side or edge view of the same. Fig. 3 is a perspective view of a portion of a sheet of roofing 15 material, showing the flanges upon one side bent ready for use. Fig. 4 is a like view of the opposite side of a sheet, showing my improved locking-clamp as applied thereto when ready for use. Fig. 5 is a perspective view in detail 20 of said clamp; and Fig. 6 is an enlarged end view in detail of a finished seam, to more clearly illustrate the respective positions of the various parts.

Like letters of reference indicate like parts 25 in the different figures.

The object of my invention is to provide a simple, cheap, and efficient means for clamping together the standing seams of sheet-metal roofs, so that a saving of material may be effected in the seams themselves, the usual cap 30 may be dispensed with, and the sheets or sections prepared at and sent out from the shop with the clamps so attached thereto that they may be easily and rapidly bent and compressed 35 when the flanges of the sheets are connected together, thus enabling a roof to be laid very rapidly and by comparatively unskilled artisans, all of which I accomplish substantially in the manner hereinafter more particularly 40 described and claimed.

A in the drawings indicates the plates or sections of a sheet-metal roof, each of which is provided with the upturned flanges A' A², which are in turn bent downwardly, forming 45 depending flanges a a'. A series of sheet-metal clamps, B, having flanges b bent upwardly between the flange a and part A', are attached to each sheet or section, said parts being bent over and made to conform to the 50 vertical and horizontal parts of said sections, as clearly shown in the drawings. Fig. 5 represents one of said clamps detached and as it is formed when applied to the plates. After placing a sufficient number of said clamps in

position in the manner stated upon a given 55 sheet, the flange a' of the next succeeding sheet is placed thereover, as shown at the right in Figs. 1 and 2, when each of the clamps B is bent upwardly over the flange a', and thence downwardly and parallel with the part A², as 60 clearly shown in Figs. 2 and 6, said clamp when finally bent forming six parallel parts—viz., b b' b² b³ b⁴, as shown at Figs. 2 and 6. When the parts B are thus bent over and compressed, the respective plates of the roof 65 are securely connected together and require no further fastening.

The parts B may be placed upon the sheets and formed therewith in a crimping-machine, and shipped in this form, so that the plates 70 may be laid in the desired positions with the flanges overlapping each other, when it is only necessary to bend the clamps B over the flange of the uppermost plate and in the direction indicated by the arrow in Fig. 2 to complete 75 the work. It is thus apparent that with said improved clamp a roof may be laid very rapidly by unskilled workmen, and that a great saving of material may be effected.

Having thus described my invention, I 80 claim—

1. In a sheet-metal roof, the sections A, the edges A' A² of which are respectively bent vertically and downwardly so as to form depending flanges a a', in combination with a series of detachable sheet-metal cleats or clamps, B, one end of each being so bent as to conform to and clasp both sides of the flange a, one portion of said clamp being parallel with the part A' and the remaining portion bent upwardly, and thence downwardly so as to embrace the outside of the flanges a' A², whereby two sections, A, may be held together, substantially as shown and described. 85

2. In a sheet-metal roof, the sections A, having upwardly-bent flanges A' A² and downwardly-bent flanges a a', in combination with a series of sheet-metal clamps bent alternately in opposite directions around and over the flanges a a', respectively, so as to form the 90 parts b b' b² b³ b⁴ approximately parallel with each other in the finished seam, substantially as and for the purposes set forth. 95

FRANK. E. SAGENDORPH.
